UNITED STATES PATENT OFFICE

136,580

DESIGN FOR AN AIRPLANE

Robert J. Woods, Grand Island, N. Y., assignor to
Bell Aircraft Corporation, Buffalo, N. Y.

Application March 23, 1943, Serial No. 109,807

Term of patent 14 years

To all whom it may concern:

Be it known that I, Robert J. Woods, a citizen of the United States, residing at Grand Island, in the county of Erie and State of New York, have invented a new, original, and ornamental Design for an Airplane, of which the following is a specification, reference being had to the accompanying drawing forming part thereof.

Fig. 1 is a top plan of an airplane embodying my new design;

Fig. 2 is a front elevational view thereof; and
Fig. 3 is a side elevational view thereof.

I claim:

The ornamental design for an airplane, as shown.

ROBERT J. WOODS.
